Primary Examiner — Dominic Simone(74) Attorney, Agent, or Firm — Banner & Witcoff, Ltd.(57) CLAIM

The ornamental design for a shoe upper with wrap-around panel, as shown and described.

DESCRIPTION

FIG. 1 is a toe end view of a shoe upper with wrap-around panel showing my new design;

FIG. 2 is a heel end view thereof;

FIG. 3 is a lateral side view thereof;

FIG. 4 is a medial side view thereof;

FIG. 5 is a top view thereof;

FIG. 6 is a bottom view thereof; and,

FIG. 7 is a front perspective view thereof.

The broken lines showing of the vertical stitch seam in the rear of the upper and the remainder of the shoe are for environmental purposes only and form no part of the claimed design.
